UNITED STATES PATENT OFFICE.

NATHAN LIEBERFREUND, OF PASSAIC, NEW JERSEY.

DESIGN FOR A CHARM.

60,928.

Specification for Design. Patented May 2, 1922.

Application filed November 29, 1921. Serial No. 518,702. Term of patent 3½ years.

To all whom it may concern:

Be it known that I, NATHAN LIEBERFREUND, a citizen of the United States, residing at Passaic, in the county of Passaic and State of New Jersey, have invented a new, original, and ornamental Design for Charms, of which the following is a specification, reference being had to the accompanying drawing, forming part thereof.

Wherein the figure is a front view of a charm, showing my new design, the lettering on the panels thereof being fanciful and illustrative only.

I claim:

The ornamental design for a charm as shown.

Signed at New York, borough of Manhattan, in the county of New York and State of New York, this 23rd day of November, 1921, before two subscribing witnesses.

NATHAN LIEBERFREUND.
